(57) **CLAIM**

The ornamental design for a mobile phone hardshell case, substantially as shown and described.

DESCRIPTION

FIG. 1 is a front perspective view of a mobile phone hardshell case showing the new design;

FIG. 2 is front elevation of the case shown in FIG. 1;

FIG. 3 is rear view of the case in relation to FIG. 2;

FIG. 4 is a left side view of the case in relation to FIG. 2;

FIG. 5 is a right side view of the case in relation to FIG. 2;

FIG. 6 is a top view of the case in relation to FIG. 2;

FIG. 7 is a bottom view of the case in relation to FIG. 2;

FIG. 8 is a front perspective view of the case in an open position;

FIG. 9 is a front view of the case in an open position;

FIG. 10 is a back view of the case in an open position;

FIG. 11 is a left side view of the case in relation to FIG. 9;

FIG. 12 is a right side view of the case in relation to FIG. 9;

FIG. 13 is a top view of the case in relation to FIG. 9; and,

FIG. 14 is a bottom view of the case in relation to FIG. 9.

The broken lines depict stitching which is part of the claimed design.
